UNITED STATES PATENT OFFICE.

MADS M. LARSEN, OF COLTON, CALIFORNIA.

COLLAPSIBLE CABINET.

Application filed September 22, 1922. Serial No. 589,824.

To all whom it may concern:

Be it known that I, MADS M. LARSEN, a citizen of the United States, residing at Colton, in the county of San Bernardino and State of California, have invented new and useful Improvements in Collapsible Cabinets, of which the following is a specification.

This invention relates to receptacles, and particularly to a collapsible, fabric-walled article for containing various articles of food and other substances, as may be desired.

It is an object of the invention to provide a collapsible fabric-walled cabinet or receptacle which may be constructed in any suitable dimensions and capacity. It is also an object to provide a fabric-walled collapsible receptacle of sanitary construction and which will provide for a desired degree of ventilation to preserve the contents for a reasonable period. Another object of the invention is to provide a collapsible, camp or out-door, food cabinet.

Other objects and advantages will be made manifest in the following specification of an embodiment of the invention illustrated in the accompanying drawings, wherein:

Figure 1 is a perspective of the cabinet in extended suspended position ready for use;

Figure 2 is a vertical transverse section through the device;

Figure 3 is a longitudinal central section showing the cabinet collapsed;

Figure 4 is a perspective showing the guide strip and the attached portion of the flap of the wall.

The device is shown as comprising a fabric wall or exterior such as stout canvas 2 of suitable height, the top edge being appropriately connected to a top member 3 and the bottom edge to a bottom member 4 of the cabinet, these being shown as of elongated form and having rounded ends 5. One or more intermediate shelves 6 may be introduced between the top and bottom members, and these shelves are appropriately secured to the fabric wall 2 as by screws, tacks or other suitable fastening means 7, as are likewise the top and bottom members. The fabric wall has meeting flap edges, preferably designed to overlap in the closed position, as shown in Figure 1, and these meeting edges are provided with suitable devices for temporarily fastening the

same in closed position. Such fastening devices may consist of snap fasteners, buckles or latches of any suitable type, and are conventionally indicated at 8. To provide a sufficiently tight closure at the lapping portions of the fabric in the front of the cabinet, the top and bottom edges of the flaps are provided with loops 10 to receive guide straps 11 which fasten as at 12 along the front edge of the top and bottom members 3 and 4. This enables the flap portions to be shifted along the top and bottom edges to a fully open position of desired extent and when the flaps are drawn together and fastened the guide straps hold the flaps in close to the contiguous parts and thus form a sufficiently tight joint to keep out flying insects.

To the top member 3 and upper portion of the fabric wall there are attached suspending loops 13 extending transversely across the top 3 and being attached to the contiguous ends of a top bar 14 extending longitudinally of the top and being provided with a hanger in the form of a piece of rope or other suitable element 15. By this means the collapsible cabinet can be readily suspended from any primary support, as upon the outside of a wall, or from the roof of a porch, or from the limb of a tree in cases where the device is being utilized by campers for storage of food supplies.

The flexible wall enables the device when not in use to be compactly folded with the shelves and top and bottom members in close position for storage and transportation.

Further embodiments, modifications and variations may be resorted to within the scope of the invention as claimed.

What is claimed is:

A collapsible cooling cabinet, comprising a plurality of superposed shelves, a fabric wall secured to the edges of such shelves, suspending loops having their ends secured to the fabric wall and to the uppermost shelf and extending transversely there across, a top bar secured to the centers of said loops, fabric members secured to the ends of said top bar and to the ends of the uppermost shelf, and a rope hanger secured adjacent the ends of said top bar.

In testimony whereof I have signed my name to this specification.

MADS M. LARSEN.
